UNITED STATES PATENT OFFICE.

PIERRE MAYRAND, OF MONTREAL, QUEBEC, CANADA.

CAR-COUPING.

SPECIFICATION forming part of Letters Patent No. 291,210, dated January 1, 1884.

Application filed October 27, 1883. (No model.)

To all whom it may concern:

Be it known that I, PIERRE MAYRAND, of the city and district of Montreal, in the Province of Quebec, Canada, have invented certain new and useful Improvements in Railway-Car Couplers; and I do hereby declare the following to be a full, clear, and exact description of the same.

The object of my invention is to provide a coupler for all kinds of railway-cars that can be handled from the top or sides of the car, thereby precluding any necessity of the operator's going between the cars, and the accompanying risk of accident or possible injury. I attain this object by the mechanism illustrated in the accompanying drawings, in which—

Figure 1 is a side elevation of parts of two railway-cars connected by my improved coupler. Fig. 2 is a plan view of the coupler in connection. Fig. 3 is a longitudinal mid-section drawn to a larger scale. Figs. 4 and 5 are face views of the two parts of the same. Fig. 6 is a part section of the car whose coupler carries the coupling-pin.

A and B are the draw-heads, the former carrying the link *a*, and the latter the coupling-pin *b*.

C is a shaft journaled in the frame-work of the car, and extending out past the sides of the same. On the ends of this shaft, and overhanging the sides of the car, are the hand-wheels *c c*, by which the shaft *C* is rotated, and by which, also, as will be seen from the following, the coupling-pin may be raised when required. *d* is a lifting-arm, fixed rigidly on the shaft by set-screws or in any other approved manner. It extends outward and up over the draw-head, where it is attached to the head of the coupling-pin.

a' is a lifting-lever, also keyed to the shaft *C*, and extends out past the end of the car, where it is attached to the lower end of the lifting-rod *e*, which extends upward to the top of the car in the case of a box-car, thus bringing the control of the coupling-pin within reach of a person on the roof of the car. In passenger-cars the rod *e* may extend only to the top of the platform hand-rail, so that a per-

son on the platform can raise the pin without going between the cars. *e'* is a guide for the coupling-pin when it is drawn up. It is simply an upright case having an opening made in its front side, through which the connection of the coupling-pin *b* with the lifting-arm *d* passes. The guide may be lifted out of the bed-piece *b'*, which holds it to the car-frame, when required. The pin is held up by the device shown in Fig. 5, which I will now describe. On the shaft *c* is fixed a lever, *D*, whose short arm is held up by a shoulder of the upper arm of the latch-lever *E*, which is held against said short arm by the spring *f*. The other end of this spring is attached to the long arm of the lever *D*, which it throws up immediately the shoulder of the latch-lever above mentioned is withdrawn.

g is a bar attached to the lower end of the latch-lever *E*, projecting out from the end of the car, and which, when pressed inward, disengages the latch and allows the spring *f* to throw down the pin *b*. The rod *e* and its connection with the shaft *C* are common to both cars—the car whose draw-head carries the pin and the car which carries the link. In the latter, however, the lifting-arm *d* is connected to the link *a* by the eyebolt *h*, instead of to a coupling-pin, as in the other draw-head. By this arrangement the outer end of the link may be raised when necessary, so as to enter the coupler of an approaching car.

The car which carries the link also carries the coupling-arm *i*, which meets and presses against the bar *g* when the cars are brought together, and in the manner above described causes the coupling-pin to drop through the link as soon as it is in place in the draw-head.

What I claim as my invention is—

1. In a railway-car coupler, the transverse shaft *C*, having the hand-wheels *c c*, the lifting-arm *d*, connected with the coupling-pin *b*, the lever *D*, fixed rigidly to the shaft *C*, the latch-lever *E*, spring *f*, and the bar *g*, substantially as shown and described.

2. In a railway-car coupler, the shaft *C*, on which is fixed the lifting-arm *d*, connected with the coupling-link *a* by the eyebolt *h*, so

that the link may be raised by operating the hand-wheels *c* or the lifting-rod *e*, as shown and described.

3. In a railway-car coupler, the combination of the lifting-rod *e* with the coupling-link *a*, lifting-arm *d*, and shaft *C*, substantially as described.

4. The combination of the lifting-rod *e* with the coupling-pin *b*, lifting-arm *d*, shaft *C*, lever

D, latch-lever *E*, and spring *f*, substantially as shown and described.

PIERRE MAYRAND.
